No. 893,264.

PATENTED JULY 14, 1908.

W. H. REYNOLDS.
SWINGING DESK STAND.
APPLICATION FILED AUG. 2, 1907.

UNITED STATES PATENT OFFICE.

WILLIAM H. REYNOLDS, OF TOLEDO, OHIO, ASSIGNOR TO THE MEILINK MANUFACTURING COMPANY, OF TOLEDO, OHIO, A CORPORATION OF OHIO.

SWINGING DESK-STAND.

No. 893,264.

Specification of Letters Patent.

Patented July 14, 1908.

Application filed August 2, 1907. Serial No. 386,732.

To all whom it may concern:

Be it known that I, WILLIAM H. REYNOLDS, a citizen of the United States, residing at Toledo, in the county of Lucas and State 5 of Ohio, have invented a new and useful Swinging Desk-Stand, of which the following is a specification.

This invention relates to an attachment in the form of a stand or platform.

10 This invention has utility when adapted as a swinging desk stand which may be rigidly locked in any angular position.

Referring to the drawings: Figure 1 is a perspective view looking upward toward the 15 underside of an embodiment of the invention in a swinging desk stand; Fig. 2 is a perspective view of such stand swung away from front of desk; Fig. 3 is a plan view of upper bracket, and Fig. 4 is a plan view of lower 20 bracket.

To a support, as desk 1, may be attached upper bracket 2 and lower bracket 3 by means of screws. Extending into the aligned holes of these brackets or hinge members is 25 pivot rod 4, the upper end of which extends through pivot hole in ear at axial corner of frame 5 while lower end of rod 4 rests on shoulder 3' in bracket 3. The shoulder 3' in bracket 3 accordingly forms two opposing 30 cup-shaped seats for the rod 4. Adjacent this axial corner of frame 5 and extending from the lower side of said frame is angular lug 6, which carries thumb screw 7 operable to clamp curved rim 8 of hinge bracket 2. The 35 square frame 5 has its axial corner sustained by bracket 2, and by set screw 7 this swinging frame may be rigidly locked in any angular position.

Extending to each of the three remote corners of frame 5 is a rod or element 9 firmly riveted in the frame and extending to block 10 where the rods 9 are also firmly held. Pivot rod 4 extends through block 10. Hinge bracket 3 is close up against lower side 45 of block 10, thereby rendering frame 5 stiff as to the remote corners, while hinge bracket 2 coacts to prevent any play of frame at adjacent or axial corner thereof.

Bolts 11 extending through frame 5 attach 50 the top or platform 12 to the swinging stand.

The brackets 2, 3, may be so placed as to height that the top or platform will be in the most convenient position, as for a typewriter, card index boxes, telephone or other purpose, and as these brackets are reversible, attachment may be made at either end of the desk to have the stand swing from front side to an out-of-the-way position as to the worker at the desk. Frame 5 and top 12 are each 55 rectangular, but the former is square while the latter is oblong, thus permitting of combining in two ways—to have long way of top 12 parallel when swung into position in front of desk, or have long way of top 12 perpendicular to front line of desk. These adjustments multiply the adaptabilities of the construction, making possible always most advantageous use, and when combined with the clamp feature insure that stand will not only be stiff but will stay in any position of adjustment within the limit of swing. A fixed 60 medial position for the stand is an adjustment most usual for miscellaneous use. There is no vertical vibration permitted in the stand as lug 6 fixes the position of axial 65 corner of frame 5. The stand as a stand is fixed to swing in but the plane in which set, and the independent locking action fixes the position of the stand in this plane against movement in either direction. The structure in its simplicity embodies a maximum 70 of rigidity and strength, making it of exceptional value as an article of office furniture. 75

What is claimed and it is desired to secure by Letters Patent is:

1. A platform, a pair of sustaining brackets therefor, a pivot rod extending into the brackets, means rigid with the platform engaging the rod and directly coacting with one bracket to sustain a portion of the platform adjacent to the rod, and means rigid with the platform engaging the rod and directly coacting with the other bracket to sustain the portions of the platform remote from the rod. 90

2. A platform, a pair of fixed vertically 95 arranged platform sustaining brackets relative to which the platform is swingable, the upper of said brackets directly sustaining adjacent portion of said platform, and means supported in contact with the lower bracket 100

engaging only the remote portions of the platform.

3. A platform, a pair of fixed vertically arranged platform holding brackets relatively to which the platform is swingable, and a locking device between one of the brackets and the platform comprising a rigidly held segment on one of the parts and clamping means on the other part whereby

the segment and clamp coact to positively 10 keep the platform in adjusted position.

In testimony whereof I affix my signature in the presence of two witnesses.

WM. H. REYNOLDS.
